UNITED STATES PATENT OFFICE.

JOSEPH AVVOCATO, OF BROOKLYN, NEW YORK.

DESIGN FOR SPOONS, KNIVES, FORKS, OR SIMILAR ARTICLES OF TABLEWARE.

Application filed June 7, 1922. Serial No. 2,552. Term of patent 3½ years.

To all whom it may concern:

Be it known that I, JOSEPH AVVOCATO, a citizen of the United States of America, residing in the borough of Brooklyn, county of Kings, city and State of New York, have invented a new, original, and ornamental Design for Spoons, Knives, Forks, or Similar Articles of Tableware.

The figure represents a front view of a spoon showing my new design.

I claim:

The ornamental design for spoons, knives, forks, or similar articles of tableware, as shown.

JOSEPH AVVOCATO.

Witnesses:

P. J. HUBBARD,
F. W. LUCE.
